[57] CLAIM

The ornamental design for a bottle, as shown and described.

DESCRIPTION

FIG. 1 is a front elevation of a bottle showing my new design, the rear elevation is a mirror image thereto except for the conventional screw threading on the bottle neck;

FIG. 2 is a left side elevational view thereof;

FIG. 3 is a right side elevational view thereof;

FIG. 4 is a top plan view thereof;

FIG. 5 is a bottom plan view thereof;

FIG. 6 is a cross-sectional view taken on the line 6—6 of FIG. 1;

FIG. 7 is a cross-sectional view taken on the line 7—7 of FIG. 1; and,

FIG. 8 is a cross-sectional view taken on the line 8—8 of FIG. 1.
